IGNITION DEVICE

Louis Beeh and Wolfgang E. Schwarzmamn,
Longmeadow, Mass., assignors to United Amer-
ican Bosch Corporation, Springfield, Mass., a
Corporation of New York

Application March 22, 1932. Serial No. 600,446

11 Claims. (Cl. 123—148)

Our invention relates to improvements in ignition devices and particularly to a dual timer-distributor unit for internal combustion engines.

An object of the invention is to provide a compact ignition device of this type for aeroplane engines, with a view to saving space and permitting the addition of auxiliary apparatus needed in the operation of such engines.

It is now the practice to equip aeroplane engines in many instances with two magnetos which have independent drive shafts; and which may be located on the same side or on different sides of the engine. This arrangement of course requires a great deal of room and the disposition of accessories, such as a generator for starting purposes and to furnish current for lighting the aeroplane, is often a difficult problem. Our invention aims to remedy this state of affairs; for our improved dual timer-distributor unit is adapted to displace both magnetos; occupying the position of one of them and making the space otherwise needed by the other available for the location of a different unit, such as a generator for lighting and starting, or some other necessary piece of apparatus. With our timer-distributor unit mounted on such an engine, ignition is produced by means of a coil or coils and current drawn from the battery by which the starting of the engine is effected in the first place.

Another object of our invention is to provide a timer-distributor unit that can be driven in the same manner as a magneto; has preferably the same approximate shape; and while the size thereof is restricted within proper limits, is yet large enough to assure efficient and certain operation at all altitudes and all other conditions of running.

A still further object of the invention is to provide a dual timer-distributor unit having separate distributors which are independently enclosed and timing devices mounted in a single compartment to cooperate separately therewith.

With these and other objects and advantages, the invention consists in the novel features specified in the appended claims; and by way of example, a construction according to the invention is described hereinafter wherein:

Fig. 1 is an end view of a timer distributor unit according to our invention;

Fig. 2 is a vertical section on the line 2—2 of Fig. 1;

Fig. 3 is a vertical section along the line 3—3 of Fig. 2; and,

Fig. 4 is an end view showing parts of the

double timer mounted in the common casing for same, the cover for said casing being removed.

The same numerals identify the same parts throughout.

The device comprises a body 1 in the form of a housing for the driving gear; and this housing is of suitable shape and preferably formed in one piece, as by casting. At one end on the lower part of the housing is mounted the casing 2 for the timers and the other end has the form of an oppositely extending projection 3 in alignment with the housing 2. The distributors are mounted on the upper part of the housing 1 at each end, one above the casing 2 and the other above the projection 3; and the two distributors 4 are enveloped by metal radio shields 5. On the outer end of the projection 3 is a closure 6, the rim 7 of which fits against the projection, and this closure has a central opening 8 with an inside shoulder to provide a seat for an antifriction bearing 9 which receives one end of a drive shaft 10. The other end of this shaft is mounted in a similar bearing 11 in the opposite end of the housing and this end of the shaft projects through an opening in said opposite end and enters the casing 2.

Adjacent the end carrying the casing 2, the housing 1 has a vertical extension 12 on the opposite faces of which the casing of the distributors 4 and the radio shields 5 are supported. This extension bulges along one side as indicated at 13, and in the upper part thereof is mounted in suitable antifriction bearings a shaft 14 by which the rotors of the two distributors 90 are actuated. This shaft is parallel with the shaft 10, which carries fast thereon in line with the extension 12 a suitable gear 15. This gear meshes with a similar gear 16 at the lower end of a vertical shaft 17, turning in suitable anti-friction bearing at the top and bottom of the housing and carrying another rigidly attached gear 18 which meshes with a gear 19 on the shaft 14. As shown in Fig. 3, shafts 10 and 14 are mounted towards one side of the housing 1 while the shaft 17 is more towards the opposite side and gears 16 and 18 thereon are received in the bulging portion 13 of the extension 12. The unit is therefore of moderate height and no great width so that it can be mounted easily on one of the magneto supports of the engine; and the shaft 10 is connected to the drive shaft for said magneto to be readily operated. The timing devices in the casing 2 are at one end of the shaft 10 and this shaft, as shown, pro-

jects from the opposite end or projection 3 at the lower part of the housing to be joined to the drive shaft; while the two distributors are secured to opposite ends of the housing at the 5 top, one above the casing 2 and the other above the projection 3, with the extension 12 between them.

The entire unit thus has the general shape of a magneto and can be mounted and driven in the 10 same way. It has also about the same size and the dimensions are ample for operation at high altitudes, where a substantial space between adjacent distributor terminals must be available.

The top of the extension 12 is open, as shown 15 at 20, and this opening may be closed by a plate 21 to be secured in place in any suitable way. Anti-friction bearings for the opposite ends of the shaft 17 are shown at 22 and 23. The extension 12 has its walls thickened at the top in 20 front and back and these walls are recessed to provide seats for the bearing 14. The ends of the shaft of course project to the outside of the extension 12 and on each end is fixed the rotor 24 of the distributor which is of insulation and 25 carries a brush 25 which passes over terminals 26. These terminals are mounted at suitably spaced points in the casing 27 of each distributor; and each of these casings also mounts in the usual manner in fixed position at the 30 center or some other suitable point a brush 23 which engages the rotating brush 25 in line with the axis of the shaft 14. The casing 27 of the distributors are cup-shaped and provided with an open end having an exterior shoulder 29 which is held against a suitable seat 30 on the 35 outside of the two faces of the extension 12. This seat 30 is in the form of a rim or flange which receives the shouldered rim of the distributor casing within it, as shown at 31, the corner of this rim 30 engaging the shoulder 29.

The radio shields 5 are likewise cup-shaped, enveloping the casings for the distributors and open on one side and provided with a rim thereat as indicated at 32 to fit likewise against 45 the seats 30 around the outer portions of the latter. Screws 33 may be employed to hold the radio shields in place. These shields smother radiation which otherwise might occur whenever a high tension discharge takes place at the 50 igniters of the engine. The distributor casings 4 are held in place against the seats 30 by any suitable means not shown herein. Sometimes the shields 5 will be omitted.

Each radio shield 5 may be made in two sections shown at 34 and 35 provided with apertured lugs 36 to receive screws similar to screws 33 to hold these sections together. The outer section can be removed at any time to inspect 60 the distributor under the shield. At 37 are binding posts projecting from adjacent sides of hollow outlet necks 38 at the top of these shields, these binding posts receiving the end of a conductor connected to a high tension coil or coils; 65 each of the binding posts 37 being connected to one of the brushes 28 as by a suitable conductor leading from the inner end of these binding posts to a connection for the brush 28 on the outside of the distributor casings 4. The high tension or secondary terminals 26 carried by 70 each distributor casing 4 are of course shown only diagrammatically. They will be connected to binding posts, not shown, on the outside of the distributor casing 4, and from these binding posts will lead the high tension cables to the 75

spark-plugs; these cables passing out through the necks 38.

The casing 2 will contain two timers; and at the sides of the housing 1 will be arms 39 to enable the entire housing to be adjusted. These arms may be integral with the projection 3, at the outer end thereof, and each will have therein a curved slot indicated at 40. By means of these slots the housing can be secured in adjusted position by bolts engaging any suitable fixed part, to time each spark as required. On the end of the shaft 10 in the casing 2 is a cam 41. On the bottom of the casing are metal plates 42 bearing fixed contacts 43 to be engaged and disengaged by contacts 44 on interrupter levers 45 pivoted on studs 46. The plates 42 may be in metallic connection with the bottom of the casing and with the housing 1 and the levers 45 may be insulated from these plates 42 in any suitable manner as by mounting them on fiber blocks 47 which fit the studs 48. These levers may consist of bent strips of metal bearing contacts 44 at one end and having the opposite end turned over at 48 to stiffen it and enable it to be engaged by the cam when the lever is to be moved to separate the contacts 43 and 44. Each lever is connected by a bent spring strip 49 to an upturned edge 50 of a plate 51 secured to the bottom of the casing 2 and preferably insulated therefrom. These spring strips normally actuate the levers 45 to hold the two contacts 43 and 44 in engagement. At 52 are condensers in the casing 2 mounted on plates 53. The plates 42, 51 and 53 may be all secured to the bottom of the casing by screws 54, the plates 42 and 53 being grounded on the casing and the plates 51 insulated. These latter are connected to the condensers by conductors 55; and 56 are radio-shielded binding posts which may be connected to the insulated plates 51 and to the terminals of the primary coil, or coils where separate coils are used.

The bottom of the casing has an opening which is shown at 57 to receive a boss 58 on the housing 1 and around this boss may be a packing ring 59. The casing can be adjusted on the boss 58 if desired, and held in position by any suitable fastening means.

Each timer device comprising a fixed contact 43, a movable contact 44 and one of the breaker levers 45 is of course associated with one of the distributors and works therewith to make and break the circuit of a primary coil, the secondary of which is connected to one of the binding posts 37 and rotary contacts 25. Every time the cam moves one of the interrupter levers to separate the contacts 43 and 44, one of the rotor contacts 25 will be adjacent one of the secondary terminals 26 and sparks will be produced 135 at the igniter to which the latter is connected.

With units of this type, only one is needed for ignition on engines heretofore carrying two ignition magnetos. The dual timer-distributor controls ignition in all of the cylinders of the engine 140 and the other magneto gives way to a generator for lighting and starting. The shielding of the ignition so as to prevent radiation due to the high tension current and interference with signalling is very easily accomplished. The starting is readily effected because the timers will work at all speeds; and not only are the magnetos unnecessary but also one can dispense with the impulse couplings necessary when magnetos are used for starting purposes. The cost of one 150

of these units is of course considerably less than the price which two magnetos will entail.

As shown in Fig. 4, the timer casing 2 is provided with arms 39a having slots 40a, so that the timer can be held in timed position with reference to the housing 1 by means of threaded studs, not shown, fixed to the adjacent end of the housing 1 and passing through slots 40a, to receive nuts by which the arms 39a can be made fast. This construction allows the adjustment of the timer casing independent of the housing 1. Of course, any other suitable means for turning the casing 2 on the housing 1 may be employed. Hence the entire housing can be adjusted by reason of the arms 39 and slots 40 above described; and the casing 2 can be adjusted separably if desired. If necessary, the arms 39a may be omitted from the casing 2 so that this casing need not be independently adjusted, or if the casing 2 must be mounted so as to be separably adjusted, any other type of arms in the place of arms 39a may be employed.

Of course we may make various changes in details and we are by no means limited to the exact construction hereinabove set forth.

Having described our invention, what we claim as new and desire to secure and protect by Letters Patent in the United States is:

1. A dual ignition unit comprising a housing, a pair of distributors mounted on said housing, the parts of said distributors being separately enclosed, timing devices for said distributors and a casing for said timing devices on the exterior of the housing adjacent one of said distributors and facing in the same direction as said distributor.

2. A dual ignition unit comprising a housing, a pair of distributors mounted adjacent the top of the housing and at either end of same, timing devices for said distributors and a casing for said timing devices mounted on the housing at one end adjacent the lower part thereof, said casing facing in the same direction as one of said distributors.

3. A dual ignition device comprising a housing, an operating shaft in the lower part of said housing and extending through opposite ends thereof, a timer on the exterior of the housing adjacent one projecting end of said shaft, a distributor shaft in the upper part of the housing substantially parallel to the operating shaft, gearing between the operating shaft and the distributor shaft to enable the former to operate the latter.

4. A dual ignition unit comprising a housing with a projection at the lower part adjacent one end, a vertical extension adjacent the opposite end forming the upper part, a drive shaft in the lower part, a distributor shaft in the upper part, a connecting shaft in said extension and gearing for enabling the drive shaft to rotate the distributor shaft through the connecting shaft.

5. A dual ignition unit comprising a housing having a horizontal projection at the lower part forming one end, a vertical extension at the opposite end forming the upper part of the housing, a timer casing supported on the opposite end, a drive shaft in said projection and extending into the timer casing, a distributor shaft near the top of the extension, distributors adjacent both ends of the distributor shaft mounted on the outside of said extension, a connecting shaft in said extension and gearing for enabling the drive shaft to operate the distributor shaft through said connecting shaft.

6. A dual ignition unit comprising a housing, a pair of distributors on the upper part of the housing adjacent the opposite ends thereof, a timer casing supported on the lower part of the housing at one end thereof beneath one of the distributors, and facing in the same direction as said distributor, a shaft in the lower part of said housing and extending into the casing to operate the timers, a shaft in the upper part of the casing to operate the distributors and transmission means for enabling the first shaft to rotate the second shaft.

7. A dual ignition unit comprising a housing having a horizontal projection at one end, a shaft in said casing disposed in said projection and protruding at both ends of the housing, a timer casing at the other end of the housing into which the shaft extends, the housing having a vertical extension adjacent the end supporting the timer casing to form the upper part of the housing, a distributor shaft in said extension parallel to the first-named shaft, distributor casings secured to the opposite outer faces of the extension above said projection and said timer casing, a shaft in the extension and gearing to connect said shaft to the distributor shaft and the first-named shaft, and metallic radio shields secured to the opposite faces of the extension over said distributor casings, said shields having binding posts to enable the distributors to be connected to a high tension coil and having hollow necks through which cables may pass from the distributor terminals to the igniters.

8. A dual ignition unit comprising a housing having a horizontal projection at one end, a shaft in said casing disposed in said projection and protruding at both ends of the housing, a timer casing at the other end of the housing into which the shaft extends, the housing having a vertical extension adjacent the end supporting the timer casing to form the upper part of the housing, a distributor shaft in said extension parallel to the first-named shaft, distributor casings secured to the opposite outer faces of the extension above said projection and said timer casing, a shaft in the extension, gearing to connect said shaft to the distributor shaft and first-named shaft, and metallic radio shields secured to the opposite faces of the extension over said distributor casings, said shields having binding posts to enable the distributors to be connected to a high tension coil and having hollow necks through which cables may pass from the distributor terminals to the igniters, said shields being in sections one of which can be removed to permit inspection of the distributors.

9. A dual ignition device comprising a housing, an operating shaft in the lower part of said housing and extending through opposite ends thereof, a timer on the exterior of the housing adjacent one projecting end of said shaft, a distributor shaft in the upper part of the housing substantially parallel to the operating shaft, and a substantially upright shaft and gearing between the operating shaft and the distributor shaft to enable the former to operate the latter.

10. A dual ignition unit comprising a housing with a projection at the lower part adjacent one end, a vertical extension adjacent the opposite end forming the upper part, a drive shaft in the lower part, a distributor shaft in the upper part, a substantially upright connecting shaft in said extension and gearing for

enabling the drive shaft to rotate the distributor shaft through the connecting shaft.

11. A dual ignition unit comprising a housing having a horizontal projection at the lower part forming one end, a vertical extension at the opposite end forming the upper part of the housing, a timer casing supported on the opposite end, a drive shaft in said projection and extending into the timer casing, a distributor

shaft near the top of the extension, distributors adjacent both ends of the distributor shaft mounted on the outside of said extension, a substantially upright connecting shaft in said extension and gearing for enabling the drive shaft to operate the distributor shaft through said connecting shaft. 80
